LITTER RECEPTACLE

Eleanor V. Kingsley, 1510 W. Service Ave.,
Pomona, Calif.

Filed Apr. 5, 1965, Ser. No. 84,599

Term of patent 14 years

(Cl. 58—17)

I claim:
The ornamental design for a litter receptacle, as shown.
